UNITED STATES PATENT OFFICE.

FREDERICH W. WOOD, OF KANSAS CITY, MISSOURI.

PNEUMATIC-ACTION FOR MUSICAL INSTRUMENTS.

SPECIFICATION forming part of Letters Patent No. 794,911, dated July 18, 1905.

Application filed March 31, 1905. Serial No. 253,202.

To all whom it may concern:

Be it known that I, FREDERICH W. Wood, a citizen of the United States, residing at Kansas City, in the county of Jackson and State of Missouri, have invented certain new and useful Improvements in Pneumatic-Actions for Musical Instruments, of which the following is a specification.

This invention relates to pneumatic-actions for musical instruments, and has for its object to produce a valve mechanism which will adapt itself to its seats without regard to whether the seats are disposed exactly at right angles to the valves or not.

15 A further object is to produce a valve construction which does not require the valve-opening to be of larger size than usual, and yet permits of the passage of the necessary volume of air to effect the instantaneous action of the pneumatics.

To these ends the invention consists in certain novel and peculiar features of construction and organization, as hereinafter described and claimed, and in order that it may 20 be fully understood reference is to be had to the accompanying drawings, in which—

Figure 1 represents a vertical transverse section of the pneumatic - action, the section being taken mainly in the plane of line I I of Fig. 2. Fig. 2 is a section on the line II II of Fig. 1. Fig. 3 is an enlarged vertical section similar to the upper part of Fig. 1, but showing the lower valve-seat distorted or at an angle to the upper one. Fig. 4 is a 35 vertical section showing the type of valve in common use, said figure showing the stem thrown out of plumb slightly.

Referring now to the drawings, where like reference characters identify corresponding 40 parts, 1 indicates the exhaust-chamber of the pneumatic-action mechanism, the same exhausting into the equalizer (not shown) and then to the pumps, also not shown, because these parts are of common and well-known 45 construction and have nothing to do with the present invention. A pneumatic 2 for each tracker-bar opening, the tracker-bar being also omitted because forming no part of this invention, is secured to the under side of the 50 bottom of the exhaust-chamber and is adapt-

ed to be connected in the usual or any preferred manner to operate the musical instrument—for instance, a piano—and for each pneumatic there are a passage 3 and a valve-chamber 4, each valve-chamber opening into 55 the exhaust-chamber through its opening 5 and to the atmosphere through its opening 6, said openings being bridged at their lower and upper sides, respectively, by guide-bars 7 for the valve-stems 8, each stem resting at its 60 lower end on a block 9, secured to the flexible diaphragm 10. This diaphragm may be of leather or rubber, preferably the latter, because there is less danger of leakage of air through it and may extend the full length of 65 the exhaust-chamber and bridge cavities 11 in the bottom thereof equal in number to the valves, or there may be a diaphragm 10 for each valve, the diaphragm bridging the cavity or recess 11 in the upper side of a block 12, secured on the bottom of the exhaust-chamber. In order to prevent noise when a block 9 strikes the bottom of a cavity 11, each block 12 is provided with a cushion 13.

14 is a passage for each valve below the 75 exhaust-chamber, one end opening into cavity 11 directly, as shown in Fig. 3, or into said cavity through an aperture 15 in block 12 and cushion 13, as shown in Fig. 1. At its opposite end each passage 14 is provided 80 with a connecting-tube 16, leading to the tracker-bar in the usual manner, and said passage is provided with a fine partitioning-screen 17 to exclude from the valve mechanism any small foreign particles which may 85 be drawn into the tracker-bar, and connecting each passage 14 with the exhaust-chamber between the screen and diaphragm is a vent-passage 18.

A valve for alternately closing and uncovering the aligned openings 5 and 6 consists of two similar members, each comprising the frustum-shaped body portion 19, fitting loosely on stem 8, and the outer portion or flange 20 projecting from the base of the 95 frustum-shaped portion, the lower member being upright and the upper member inverted, so that their apices may bear against the interposed washer or washers 21, mounted to slide upon and have a substantially air- 100

tight relation with the stem, a collar or shoulder 22, rigidly secured to or formed with the stem within the frustum-shaped body of the lower member, serving to lift said members when the stem rises. To make the joint noiseless and air-tight between the flange of the lower member and the bottom of the valve-chamber, a cushion 23 is provided, the same being preferably secured to the bottom of the chamber, and to make the joint between the flange of the upper member and the top of said chamber air-tight said upper member is provided with a cushion 24.

In order to prevent the hissing sound attendant upon a rush of air past a hard surface, the top of the valve-chamber is also lined with leather or its equivalent, as at 25.

As well known, when the machine is in operation air is being continuously exhausted from chamber 1 through the equalizer and pumps, so that said chamber is practically a vacuum-chamber. When the tracker-bar opening communicating with a tube 16 is closed by a non-perforated portion of the note-sheet, diaphragm 10 is depressed, and the valve is closing opening 5 and uncovering opening 6 to admit air therethrough and through chamber 4 and passage 3 to the pneumatic 2, which is therefore inflated, it being understood that the vent-passage 18 permits the air below diaphragm 10 to be likewise exhausted into and from the vacuum-chamber, as otherwise the diaphragm could not be depressed.

Now when a perforation in the note-sheet or roll of paper registers with the tracker-bar opening referred to, air enters the tracker-bar and because the cavity 11 is of greater area than the surface of the valve raises the diaphragm and its valve, and thereby uncovers opening 5 and covers opening 6, this result being instantly followed by the exhaustion of air from and consequent collapse of the pneumatic, the collapse of the pneumatic resulting in the operation of the musical instrument—viz., in the operation of a key of the piano and in the consequent production of sound—it being understood in this connection that the vent-passage is so small that the small quantity of air which passes through it into the exhaust-chamber offers no material resistance to the upward movement of the diaphragm. As the progress of the note-sheet again results in closing the tracker-bar opening the parts resume their original positions and the weight of the mechanism between the pneumatic and the piano, added to the gravitational tendency of the former and the rush of air therein, effects the instant re-expansion of the pneumatic. All subsequent operations are repetitions of those described.

It will be seen that as the air rushes into the pneumatic when the parts are disposed as shown the cushioned surfaces 24 and 25

prevent any hissing sound and that the various cushions deaden or prevent any sound which would naturally follow the impact of the valve or other part against the arresting-surfaces, this being true on both the upward- 70 and downward movement.

In view of the fact that the valve members are loosely mounted on the stem it is obvious that any slight distortion of the parts, such as shown in Figs. 3 and 4, due to warpage or 75 imperfect assemblage of the parts, does not result in an imperfect seating of the valves, because the valve members are free to assume different angles to the axis of the stem, and thus bear snugly against their respective 80 seats, the angular position of either member not resulting in the passage of air through the opening in its apex, because of the closely-fitting washer or washers 21, which washer or washers, because of compressible material, 85 yield to permit such angular relation of the valve members.

It will also be noticed that the hollow conical form of the lower member permits the collar which elevates the valve with the stem 90 to occupy a position above the flange of the lower member, and therefore does not at any time obstruct the passage of air through opening 5, whereas with the type of valve shown in Fig. 4 said collar is never wholly withdrawn from opening 5 and by occupying the same obstructs the passage of air to some extent, the result being a slower collapse of the pneumatic than would otherwise occur.

The peculiar type of valve shown by me 100 furthermore provides a more extended bearing surface or area than that shown by Fig. 4 and in addition concentrates the air against the center of the valve, and thereby more efficiently and reliably operates the same, it being noticed in this connection that dispensed with the use of a collar on the valve - stem above the upper member, as the same has been found superfluous in practice.

From the above description it will be apparent that I have produced a pneumatic-action for musical instruments which embodies the features of advantage enumerated as desirable in the statement of invention and which obviously is susceptible of modification in some particulars without departing from the principle of construction involved.

Having thus described the invention, what I claim as new, and desire to secure by Letters Patent, is—

1. In a pneumatic-action for musical instruments, a valve-chamber having aligned openings, a reciprocatory valve-stem extending through said openings and suitably guided, valve members mounted loosely on said stem, one to control one of the valve-openings and the other the other valve-opening, a compressible washer or washers fitting slidingly and with a substantially air-tight 130

relation on said stem between said members, and means rigid with the valve-stem for moving said valves simultaneously to uncover one valve-opening and cover the other.

- 5 2. In a pneumatic-action for musical instruments, a valve-chamber having alined openings, a reciprocatory valve-stem extending through said openings and suitably guided, valve members mounted loosely on 10 said stem, one to control one of the valve-openings and the other the other valve-opening, and comprising substantially frustum-shaped portions inverted with respect to each other, a compressible washer or washers 15 fitting slidingly and with a substantially airtight relation on said stem between said members, and means rigid with the valve-stem for moving said valves to uncover one valve-opening and cover the other.
- 20 3. In a pneumatic-action for musical instruments, a valve-chamber having alined openings, a reciprocatory valve-stem extending through said openings and suitably guided, valve members mounted loosely on 25 said stem, one to control one of the valve-openings and the other the other valve-opening, and comprising substantially frustum-shaped portions inverted with respect to each other, a compressible washer or washers 30 fitting slidingly and with a substantially airtight relation on said stem between said members, and a collar or shoulder rigid with

said valve-stem and occupying the hollow of the frustum-shaped body portion of one of said valves so that when the stem is moved 35 in the proper direction, said collar shall unseat said valve member and seat the other valve member.

4. In a pneumatic-action for musical instruments, a valve-chamber having alined 40 openings, an upright reciprocatory valve-stem extending through said openings and suitably guided, valve members mounted loosely on said stem, one to control the lower valve-opening and the other the upper valve- 45 opening, and each comprising a frustum-shaped body portion and an outwardly-projecting flange at the base of said body portion, the frustum-shaped body portion of the lower member projecting upwardly and that 50 of the upper member downwardly, and a collar or shoulder rigid with said valve-stem and occupying the hollow of the frustum-shaped body portion of the lower member of said valve so that when the stem is moved upward 55 said collar shall unseat the lower member and seat the upper member.

In testimony whereof I affix my signature in the presence of two witnesses.

FREDERICH W. WOOD.
